UNITED STATES PATENT OFFICE.

JOHN T. PETERSON, MAYWOOD, ILLINOIS.

BLOWTORCH.

Application filed May 31, 1923. Serial No. 642,675.

To all whom it may concern:

Be it known that I, JOHN T. PETERSON, a citizen of the United States, residing at Maywood, in the county of Cook and State 5 of Illinois, have invented certain new and useful Improvements in Blowtorches, of which the following is a specification.

This invention relates to improvements in torches and has for its object to provide 10 a soldering iron or branding iron torch having a fuel super-heating chamber.

Another object of the invention is to provide a blow torch having a heating and super-heating chamber extending over and 15 approximately the full length of the burner thereof.

With the above and such other objects in view as may hereinafter more fully appear I have invented the device illustrated 20 in the accompanying drawings in which:

Figure 1 is an elevational sectional view of my improved blow torch; and

Figure 2 is a section on line 2—2 thereof.

Like reference characters indicate like 25 parts throughout the following specification and in the several views in the drawings in which 1 is a blow torch embracing a fuel tank 2, a burner 3, a heating chamber 4, a super-heating chamber 5, a feed pipe 6 to 30 the heating chamber, a generating cup 7 and a needle valve 8. The feed pipe 6 is threaded at one end to the end wall 9 of the tank 2 and at its other end into the wall 10 of the burner casting 11. The casting 11 is di- 35 vided into two cylindrical chambers the larger chamber 12 being a burner chamber and the smaller chamber 5 being a super-heating chamber which extends to adjacent the outer end 13 of said burner chamber.

40 A pipe 14 is screw threaded into the end 15 of the pipe 6 and is held suspended thereby within the chamber 5, said pipe 14 extending to very near the end wall 16 of the chamber 5, said pipe 14 being of a smaller 45 diameter than the chamber 5 and thus provides a passage for the heated gases to pass from the pipe 14 to enter the chamber 5, from which they are forced rearwardly to the vertical bore 17 which runs down from 50 the rear lower portion of the chamber 5 through the casting 11. The inner end 18 of the casting 11 is provided with an extension 19 which is threaded internally to receive the threaded valve stem 20 of said 55 needle valve 8, and externally to receive the cap 21. The valve seat 22 is screw threaded

and screws through the threaded bore 23 in the wall 24 of the burner chamber 12. The stem 20 has a right angular handle end 25, whereby the needle 8 may be adjusted. The 60 generator cup 7, has an integral plug 26 extending upwardly from its bottom wall to above the edge 27 of the cup, said plug having its upper end screw threaded to thread into the lower end of the valve chamber 17 65 whereby the member 26 forms a closure for said valve chamber and a support for said cup. A lug 28 extends from the bottom of the chamber 12 and has an opening 29 therein to receive the pin 30 which carries the 70 branding iron 31. The plug 32, screw threaded into the cap 33 carries an air pump 34 which is operated by the stem 35 which is provided by the screw portion 36 whereby said portion may be threaded into the plug 75 to prevent movement when not being used for pumping air in the tank 2.

The branding device may be removed from the torch and a soldering iron slipped or threaded into the open end thereof. 80

Having described my invention that which I claim to be new and desire to procure by Letters Patent is:

1. A blow torch including an elongated fuel tank constituting in itself a handle for 85 the torch, a feed pipe communicating with the forward end of said tank and extending forwardly therefrom in axial alignment with said tank, a casting secured at its rear end to the forward end of said feed pipe 90 and having two parallel chambers of approximately equal lengths but of different diameters, the one of larger diameter constituting the combustion chamber of the torch and the other constituting a heating 95 chamber, the latter being longitudinally aligned with said tank and feed pipe, a pipe forming an extension of said feed pipe located within said heating chamber and terminating in an open end a little to the rear 100 of the forward end of said chamber, said casting having a downwardly extending passage communicating with the rear end of said heating chamber and lying rearwardly of said combustion chamber, a needle 105 valve controlling an opening from said passage into said combustion chamber, the stem of said valve extending axially of said combustion chamber and terminating at its rear end in a handle just forward of said fuel 110 tank, and a priming cup located below said passage and the rear of the combustion

chamber, said cup having an upward extension threaded at its upper end into the lower end of said passage to close the same.

2. A blow torch including an elongated fuel tank constituting in itself a handle for the torch, a feed pipe communicating with the forward end of said tank and extending forwardly therefrom in axial alignment with said tank, a casting secured at its rear 10 end to the forward end of said feed pipe and having two parallel chambers of approximately equal lengths but of different diameters, the one of larger diameter constituting the combustion chamber of the 15 torch and the other constituting a heating chamber, the latter being longitudinally aligned with said tank and feed pipe, a pipe

forming an extension of said feed pipe located within said heating chamber and terminating in an open end a little to the rear of the forward end of said chamber, said casting having a downwardly extending passage communicating with the rear end of 20 said heating chamber and lying rearwardly of said combustion chamber, a needle valve 25 controlling an opening from said passage into said combustion chamber, the stem of said valve extending axially of said combustion chamber and terminating at its rear end in a handle just forward of said fuel tank, and a priming cup located beneath 30 said combustion chamber.

JOHN T. PETERSON.
